UNITED STATES PATENT OFFICE.

WILLIAM S. ATWOOD, OF MONTREAL, QUEBEC, CANADA, ASSIGNOR TO THE DOMINION CAR & FOUNDRY COMPANY, LIMITED, OF BLUE BONNETS, NEAR MONTREAL, CANADA, A CORPORATION OF CANADA.

SIDE STAKE FOR CARS.

No. 909,128.

Specification of Letters Patent.

Patented Jan. 5, 1909.

Application filed February 17, 1908. Serial No. 416,395.

To all whom it may concern:

Be it known that I, WILLIAM S. ATWOOD, of the city of Montreal, in the Province of Quebec and Dominion of Canada, have invented certain new and useful Improvements in Side Stakes for Cars, of which the following is a full, clear, and exact description.

This invention relates to side stakes adapted to be used in the construction of steel cars. 10 In building steel cars of various types, it is necessary to support the car body against lateral and other stresses and the object of this invention is to provide an inexpensive and efficient side stake that can preferably 15 be made of pressed steel and that will have a maximum amount of strength under compression or cross-bending with a minimum amount of material.

The device consists essentially of a steel 20 rib of U-shape having outwardly extending flanges. The rib is preferably pressed into the desired form which comprises a pair of vertical webs connected by an integral flat top member approximately at right angles 25 to the webs, said rib being tapered towards the bottom and top of the stake from a point near the base. The outwardly extending side flanges are adapted to be secured to the car body and the stake is provided with 30 strengthening braces formed integral therewith near the bottom.

In the drawings which illustrate my invention:—Figure 1 is an elevation of one end of a steel car of the hopper type showing the 35 side stakes in position. Fig. 2 is a plan view of one of the stakes. Fig. 3 is a side elevation of one of the stakes. Fig. 4 is a perspective view of same. Fig. 5 is a section on the line X—X of Fig. 2. Fig. 6 is an end 40 view of the stake.

Referring to the drawings, 1 designates a car body of the hopper type showing the side stakes 2 riveted to the upper frame at suitable distances apart, said stakes being 45 preferably made of pressed steel and gradually tapered in both directions from the strengthening braces 3 located near the lower end thereof as shown. The stake, which is U-shaped, consists of a pair of approximately 50 vertical webs 4 connected by means of the integral flat top member 5 at right angles to said webs. A pair of flanges 6 extend out-

wardly from the webs, forming the base of the stake, said flanges being secured to the car body as well as to the under frame by 55 means of the rivets 7. The strengthening braces 3, which are formed integral with the stake, are preferably pyramidal in form, being pressed outwardly from the vertical webs 4 in such a manner that the base rests 60 upon the flange 6 and gradually tapers towards the top connecting member 5. The vertical webs taper off gradually from the strengthening members to the top of the stake, as shown, and are also reduced at the 65 bottom as will be seen on reference to Figs. 3 and 4. The stakes are riveted to the car frame in such a manner that the braces 3, located near the bottom of the stake and forming the strongest part of same, are 70 designed to bear the greatest lateral stress from the car body. The top member 5, connecting the vertical webs, is flat or formed at right angles to said webs, in order that said member may have a maximum strength 75 under compression or cross-bending with a minimum amount of material.

Having thus described my invention, what I claim is:—

1. A device of the character described 80 comprising a pair of approximately vertical tapering webs connected by means of a flat top member, integral flanges extending outwardly from said webs, and strengthening braces resting on said flanges and tapering 85 towards the top of the webs, substantially as described.

2. A side stake for cars and the like comprising a U-shaped ribbed portion formed from a pair of vertical webs connected by a 90 flat top member, side flanges extending outwardly from said webs, and pyramidal strengthening braces formed integral with said webs, said ribbed portion being tapered from the strengthening braces towards both 95 ends.

3. A pressed steel side stake comprising a U-shaped ribbed portion formed from a pair of vertical webs connected by an integral flat top member, strengthening braces and side 100 flanges integral with said webs, said ribbed portion being tapered from the braces towards both ends of the stake.

4. A car comprising an upper frame hav-

ing a plurality of vertical side stakes riveted thereto, said side stakes having a ribbed portion formed from a pair of vertical webs connected by means of an integral flat top member, integral flanges extending outwardly from the vertical webs, and integral braces resting on said flanges and tapering towards the top of the ribbed portion, said ribbed

portion being tapered from the braces towards both ends of the stake. 10

In witness whereof I have hereunto set my hand in the presence of two witnesses.

WILLIAM S. ATWOOD.
